UNITED STATES PATENT OFFICE.

HENRY J. EBERHARDT, OF NEWARK, NEW JERSEY, ASSIGNOR, BY MESNE ASSIGNMENTS, TO WESTINGHOUSE ELECTRIC & MANUFACTURING COMPANY, A CORPORATION OF PENNSYLVANIA.

TRIMMER MECHANISM.

Application filed May 6, 1926. Serial No. 107,102.

My invention relates to trimming mechanisms for gear-grinding wheels and particularly to means for trimming the working surfaces of grinding wheels to contours complementary to the contours of the work to be ground.

An object of my invention is to provide a wheel-trimming device that is adapted to simultaneously shape both sides of a grinding wheel to contours identical with that of a single template.

Another object of my invention is to provide a process for grinding gear wheels that comprises mounting the grinding wheel, spindle and bearings in a removable bearing block that may be mounted in a trimming machine for trimming the wheels to a desired contour and that may be transferred to a gear-wheel grinding machine as a unit, thereby making it possible to maintain a supply of trimmed wheels that may be readily mounted on a grinding machine.

Another object of my invention is to provide a wheel-trimming device for shaping the sides and periphery of a grinding wheel to be used for finish grinding the sides of adjacent gear teeth.

Heretofore, various types of trimmer mechanisms have been utilized for trimming abrasive wheels employed for grinding gear teeth, which functioned by means of the engagement with a cam member of a guide mechanism embodying several co-operating parts for imparting a compound motion to the trimming member. Mechanisms of this character involved an indirect functioning of the guide templet that resulted in inaccuracies.

My present invention is directed to a device for trimming gear-grinding wheels that is adapted to trim both sides of the grinding wheel simultaneously to contours identical with the contour of a single guiding template.

In the accompanying drawings, Fig. 1 is a view in perspective of a trimming machine embodying my invention;

Fig. 2 is a plan view of the trimming machine of Fig. 1;

Fig. 3 is a plan view of the base of the trimming machine with the trimming slides and connecting gear wheels in place;

Figs. 4, 5 and 6 are views in plan, side elevation and end elevation, respectively, of the trimmer slide of Fig. 3. 55

Referring to the drawings, the trimmer mechanism comprises a base 1, trimming means 2 slidably mounted on the base 1, a movable bed member 3, also slidably mounted on the base 1 and having mounted thereon 60 a grinding unit 4, a motor 5, and a template 6.

The trimming means 2 comprises trimming slides 7 and 8 having rack teeth 9, that are slidably mounted in ways 10 in the 65 base 1. Gear wheels 11 mounted on studs 12 engage the rack teeth 9 and each other for interlocking the two slides 7 and 8. A plate 13 is secured to the base 1 by cap screws 14 for retaining the slides 7 and 8 70 and the gear wheels 11 in proper relation to one another and for protecting them from injury.

The plate 13 may be adjusted by means of the tapered wedge 15 to compensate for 75 wearing of the plate or slides. A guide pin 16 is provided in the trimmer slide 8 for engagement with the template 6 and a spring 17 is secured to the trimmer slide 7 for biasing it to the left, as seen in Fig. 2. The 80 force of the spring 17 is transmitted through the gear wheels 11 to the slide 8, biasing it to the right and maintaining the guide pin 16 in engagement with the template 6 thereby taking up all lost motion between the operating parts in one direction.

The template 6 is mounted on a slide 18 that is secured to the bed member 3 by means of guides 19 and 21. An adjusting screw 22 is journaled in the bed member 3 90 and has threaded engagement with the slide 18 for adjusting its position and that of the template 6 relative to the bed member 3. The bed member 3 is provided with a groove 23 for slidably engaging the tongue 24 on the 95 base 1.

A screw 25 provided with a hand wheel 26 is journaled in the base 1 parallel to and centrally disposed with respect to the tongue 24 and has threaded engagement with a nut 100 27 on the bed member 3. The grinding unit 4 comprises a bearing block 28 having a tongue 29 for engaging a groove 31 in the bed member 3 at substantially right angles

to the groove 23. A stop 32 is provided on the bed member 3 for engaging a lug 33 on the bearing block 28 to accurately locate the block 28 transversely with respect to the bed member 3. Bearings 34 are provided at either end of the bearing block 28 for supporting a spindle 35.

The spindle 35 has mounted at one end a belt pulley 36 and at the other end, a grinding wheel 37. The grinding wheel 37 is mounted upon a bushing 38 that is secured to the spindle 35 by means of the nut 39. A ring 41 is provided in the bearing block 28 to facilitate the removal of the grinding unit 4 from the trimming mechanism. The driving motor 5 is mounted upon a plate 42 on the bed member 3 and is arranged for adjustment parallel to the spindle 35. A belt 43 is provided for transmitting power from the motor 5 to the belt pulley 36.

Referring to Figs. 4, 5 and 6, the trimming slide 8 is provided with a longitudinal groove 44 and T-slots 45. A plate 46 having integral bracket members 47 and a tongue 48 for co-operating with the groove 44 is slidably mounted upon the trimmer slide 8. An adjusting screw 49 is threaded into the plate 46 and passes through a hole 51 in an elevated portion 52 of the slide 8. Nuts 53 are threaded on the adjusting screw 49 on either side of the elevated position 52 to adjust the longitudinal position of the plate 46 with respect to the slide 8.

35. A bracket member 54 having an integral lug 55 is mounted upon the plate 46 and secured thereto and to the slide 8 by a bolt 56 that extends from the T-slot 45 through holes 57 in the plate 46 and the bracket member 54 and by a bolt 58 that extends from the other T-slot 45 through a hole 59 in the plate 46 and a slot 61 in the bracket member 54. A tool-holding block 62 is pivoted on the raised portion 63 of the bracket 54 by 45 a pivot pin 64 and is held in position by a cap screw 65 that passes through a slotted opening 66 in the block 62 and is threaded into the portion 63 of the bracket 54. An adjusting screw 67 is threaded in a hole 68 50 in the block 62 and bears upon the bracket member 54 for angularly adjusting the block 62 about an axis through the pin 64.

A set screw 69 is threaded in the portion 63 of the bracket 54 for restraining the block 62 from clockwise rotation as viewed in Fig. 5. Angular adjustment of the bracket 54 about the bolt 56 may be secured by loosening the bolts 56 and 58 and turning the bracket 54 by means of set screws 71 that 60 are threaded in the brackets 47 and engage the lug member 55. A diamond-holder 72 is supported in a hole 73 in the block 62 and retained in position by the set screws 74.

65. A periphery trimmer 75 is slidably mounted in a groove 76 in the plate 13 and

may be actuated parallel to the spindle 35 by means of the hand lever 77. A diamond-holding bracket 78 is mounted on the periphery trimmer slide 75 in such manner that it may be adjusted at right angles to the groove 76 and locked in position by the bolt 79. Set screws 80 serve to secure a diamond holder 81 in the bracket 78. The diamond holders 72 and 81 are provided with hair lines 82 which serve as measuring 75 marks for determining the amount of diamond in the holder.

To operate the trimming mechanism, a gauge 83 that is supported by the diamond-holding bracket 78, is placed in position between the diamond holders 72 and diamond points 84, carried by the holders 72, are adjusted to their proper working position by manipulating the plates 46, the brackets 54 and the blocks 62, as heretofore described to bring the points 84 in contact with the edge of the gauge 83. The gauge 83 is then removed and the periphery-trimming diamond holder 81 secured in the bracket 78 and adjusted to its proper position.

90 After the adjustments are completed, the motor 5 is energized and the wheel 37 to be trimmed is rotated at a moderate speed. The hand wheel 26 is then revolved to bring the wheel 37 to be trimmed toward the trimming diamonds 84. As the wheel 37 and the bed member 3 are drawn toward the trimming diamonds, the template 6 is drawn past the guide pin 16 and the spring 17 draws the trimming diamonds 84 apart by 10 reason of its action upon the trimmer slides 7 and 8 through the cooperating gear wheels 11.

105 The trimming diamonds 84 thus trace out curves on each side of the wheel 37 that are 105 exactly identical in form and size to the curve on the template 6. The slide 18 may be adjusted by means of the adjusting screw 22 to feed the cutting diamonds 84 into engagement with the wheel 37, as successive 110 reciprocations are given to the bed member 3 by means of the hand wheel 26.

115 Light successive cuts are taken from the surface of the wheel 37 until it is brought to the desired thickness. The slide 18 and the template 6 are then withdrawn toward the front of the machine by means of the adjusting screw 22 to allow the cutting diamonds 84 to separate. The wheel 37 may then be brought into engagement with the periphery trimmer diamond 81 and reduced to the proper diameter by oscillating the hand lever 77 to take successive cuts from the surface of the wheel parallel to the spindle 35. The wheel 37 and bushing 38 may then be removed from the spindle 35 by first removing the nut 39. Or, the entire grinding unit 4 may be removed from the groove 31 in the bed member 3 with the aid of the ring 41.

Another wheel 37 or complete grinding unit 4 is then put into place and the operation repeated.

From the foregoing description, it is obvious that my invention provides a grinding-wheel trimming mechanism that is capable of rapidly and accurately forming both sides of a grinding wheel to contours identical with that of the template used and that by utilizing my invention, a supply of accurately trimmed wheels may be kept at hand for use on a grinding machine so that very little time will be lost by the grinding machine operator in replacing the grinding wheels. This method also allows one operator to become especially skilled in trimming the grinding wheels and allows another operator to become especially skilled in using the trimmed wheels in a gear-grinding or other grinding machine.

Although I have described a specific embodiment of my invention, it will be obvious to those skilled in the art that various modifications may be made in the design and details of construction of the several co-operating parts comprising my wheel-trimming mechanism without departing from the spirit and scope of my invention as set forth in the appended claims.

I claim as my invention:

1. In a trimming machine for grinding wheels, a supporting base, a bed member slidably mounted on the base, means mounted on the bed member for rotatably supporting a wheel to be trimmed, a forming template adjustably mounted on the bed member, a plurality of rack slides mounted on the base and a plurality of actuating gear wheels meshing with the rack slides and with each other, means on one rack slide for engaging the template and trimming means mounted on the rack slides.

2. In a wheel trimming machine, a support for trimming means comprising a slide member, a bracket member mounted on the slide member and angularly adjustable with respect thereto, a trimmer supporting block mounted on the bracket and angularly adjustable in a plane at an angle to the bracket adjustment plane.

3. In a trimming machine for grinding wheels, a supporting base, a bed member slidably mounted thereon, a spindle for rotatably supporting a wheel to be trimmed mounted on the bed member at substantially right angles to its direction of motion, a slide mounted on the bed member and adjustable parallel to its direction of motion, a templet mounted on the slide, two trimmer slides having rack teeth mounted on the

base, gear wheels for interlocking the trimmer slides, a guide member on one trimmer slide for co-operating with the template, resilient means for holding the guide member in engagement with the template and trimming means mounted on the trimmer slides.

4. In a trimming machine for grinding wheels a supporting base, a bed member slidably mounted thereon, a spindle for rotatably supporting a wheel to be trimmed mounted on the bed member at substantially right angles to its direction of motion, a slide mounted on the bed member and adjustable parallel to its direction of motion, a templet mounted on the slide, two trimmer slides having rack teeth mounted on the base, gear wheels for interlocking the trimmer slides, trimming means mounted on the trimmer slides, a guide member on one trimmer slide for co-operating with the template and means on the other trimmer slide for biasing the guide member into engagement with the template.

5. In a trimming machine for grinding wheels, in combination, a supporting base, a bed member slidably mounted on the base, means mounted on the bed member for rotatably supporting a wheel to be trimmed, a slide adjustably mounted on the bed member, a template mounted on the slide, two trimmer sliders having rack teeth mounted in ways on the base, a plurality of gear wheels for engaging the rack teeth to cooperatively connect the trimmer slides, trimming means for engaging the wheel to be trimmed mounted on the trimmer slides, a guide member on one of the trimmer slides for cooperating with the template to guide the trimmer slides to properly trim the wheel and resilient means for holding the guide members in engagement with the template.

6. In a trimming machine for grinding wheels, in combination, a supporting base, a bed member slidably mounted on the base, means on the bed member for rotatably supporting a wheel to be trimmed, a plurality of slide members mounted in converging ways in the base, trimming means mounted thereon, rack teeth on the slide members, gear wheels for engaging the rack teeth to interconnect the slide members, and means on the bed member for actuating the slides to trim the wheel to the desired contour.

In testimony whereof, I have hereunto subscribed my name this 15th day of April, 1926.

HENRY J. EBERHARDT.
